US0D1072168S

(12) **United States Design Patent** (10) Patent No.: **US D1,072,168 S**
(45) Date of Patent: ** Apr. 22, 2025

(54) **WATER PURIFYING MACHINE**

(71) Applicant: **QINGDAO ECOPURE FILTER CO., LTD.**, Qingdao (CN)

(72) Inventor: **Zhibin Zou**, Qingdao (CN)

(73) Assignee: **QINGDAO ECOPURE FILTER CO., LTD.**, Qingdao (CN)

(**) Term: **15 Years**

(21) Appl. No.: **29/885,849**

(22) Filed: **Mar. 1, 2023**

(51) LOC (15) Cl. **07-01**

(52) U.S. Cl. **D7/306**
USPC ....

(58) **Field of Classification Search**

(57) **CLAIM**

The ornamental design for a water purifying machine as shown and described.

DESCRIPTION

FIG. 1 is a top front perspective view of the water purifying machine showing the design, wherein the broken lines form no part of the claimed design;

FIG. 2 is a bottom front perspective view of the water purifying machine showing the design, wherein the broken lines form no part of the claimed design;

FIG. 3 is a front elevational view thereof, wherein the broken lines form no part of the claimed design, and its rear elevational view is a mirror image of the front elevational view;

FIG. 4 is a left side view thereof, wherein the broken lines form no part of the claimed design, wherein the broken lines form no part of the claimed design;

FIG. 5 is a right side view thereof, wherein the broken lines form no part of the claimed design;

FIG. 6 is a top plan view thereof, wherein the broken lines form no part of the claimed design; and,

FIG. 7 is a bottom plan view thereof, wherein the broken lines form no part of the claimed design.

1 Claim, 7 Drawing Sheets
